UNITED STATES PATENT OFFICE

LAURENCE P. DICKEY, OF MOUNTAIN LAKES, NEW JERSEY, ASSIGNOR TO AUGUST GOERTZ & CO., INC., A CORPORATION OF NEW JERSEY

VANITY BOX FOR CARRYING LOOSE FACE POWDER

Application filed September 16, 1929. Serial No. 392,829.

This invention relates to improvements in vanity boxes of the type adapted to carry loose powder.

The invention has for its principal object to provide, in a vanity box, a novel construction of loose powder compartment and closure therefor, whereby undesired sifting out of the powder is normally prevented, and yet whereby desired ejection of small quantities of the powder is readily attained, at the will of the user, by a simple manipulation of the closure.

The invention has for a further object to provide a simple self-closing loose powder compartment structure, wherein the closing element is related to the underside of the upper wall of the compartment by a pivotal connection therewith, and its free end permanently engaged by a spring-tongue tending to yieldably hold the same in closed relation to an opening in said compartment wall, all whereby a slight tapping on the closing element tends to oscillate the same so that small quantities of powder may escape around the margins thereof and onto the upper side of said upper wall of the compartment, to be thereupon accessible for use.

The invention has for another object to provide a loose powder compartment in which the upper wall section, carrying the powder ejection opening and closing element therefor, is removable to expose the interior of the compartment for replenishing the powder content.

Other objects of this invention not at this time more particularly enumerated, will be clearly understood from the following detailed description of the same.

An illustrative embodiment of the invention is shown in the accompanying drawings, in which:—

Figure 1 is a plan view of a vanity box in open condition, the same being made according to and embodying the principles of this invention; Figure 2 is a longitudinal vertical section, drawn on a larger scale, taken on line 2—2 in said Figure 1; and Figure 3 is an underside view of the removable top wall of the loose powder compartment, said view showing the manipulatable

closure for the powder ejection opening thereof.

Similar characters of reference are employed in all of the hereinabove described views, to indicate corresponding parts.

Referring to the said drawings, the reference characters 5 and 6 respectively indicate the sections of a vanity box or case, hingedly connected by the hinge structure 7 so the same may be closed one upon the other. For purposes of description the section 5 will be herein named the body section and section 6 the cover section. The sections 5 and 6 may be releasably retained in closed condition by any suitable form of latch mechanism 8.

The reference character 9 indicates a shell or frame to provide a loose powder holding compartment. Said shell or frame includes an upwardly extending annular flange 10, formed at its upper margin with an off-set annular shoulder 11, thus providing an annular seat 12 for purposes subsequently referred to. Integral with and extending horizontally from said shoulder 11 is a top flange 13, the periphery of which conforms to the interior sides of the body section 5 within which the shell or frame 9 is inserted in suitably fixed relation thereto. While I have shown the shell or frame 9 with a bottom portion overlying the inner face of the body section 5, it will be obvious that such part may be omitted and the flange 10 arranged with its lower margin abutting the inner face of the body section 5. In either case said flange 10 defines a compartment 14 in which loose powder may be carried.

Said powder compartment 14 is normally closed by a removably attached upper wall section or top-plate 15. This top plate 15 is formed with a marginal outwardly projecting bead 16 from which extends a downwardly projecting inwardly off-set annular flange 17. When said top-plate 15 is in place, the annular flange 17 frictionally telescopes into the flange 10 of the fixed compartment defining shell or frame 9, and with the bead 16 seated in the seat 12, thus not only removably relating said top plate to the shell or frame but also providing a tight

juncture between said parts to prevent sifting of the loose powder out of the compartment 14 at such points.

Said top plate 15 is provided in its body portion with an opening 18. Bordering one side or end of said opening, and preferably formed integral with said top plate body is a tubular hinge knuckle 19 projecting from the under side of said top plate. The reference character 20 indicates a closure element preferably in the form of a flat plate. This closure element is provided at one side or end with spaced hinge knuckles 21 for alignment with said hinge knuckle 19, whereby a pintle 22 may be extended through the thus aligned knuckles to thereby pivotally relate said closure element to the under side of said top plate 15. Said closure element is of an area exceeding that of the opening 18 of the top plate, so as to normally close said opening 18 when pressed upwardly against the underside of said top-plate. To yieldably retain the closure element in closed relation to said opening 18 of the top plate a spring finger 23 having a base-portion 24 is provided. The base portion 24 is fixed to the under side of said top-plate 15, by a rivet 25 or any other suitable form of fastening means, preferably in a position adjacent to the free end portion of said closure element, so that the free end of said spring finger 23 may bear yieldably against the underside of said closure element to normally thrust the same upwardly against the underside of said top plate and into closed relation to the opening 18 thereof.

When the powder compartment 14 is provided with its loose powder content, and the top plate 15 assembled with the shell or frame 40 of said compartment, the powder is adequately retained against undesired escape or sifting out, while the vanity box is carried about by the user. When the user desires to obtain an application of powder, the vanity box is opened, whereupon the user taps with the finger on the upper side of the closure element 20, where the same is exposed through the opening 18 of the top plate. This tapping action causes an oscillation of the closure element on its pivotal connection to which the spring finger 23 yields, and consequently the movement thus produced, although of small amplitude, causes a displacement of the powder sufficient to permit a small quantity thereof to escape around the interstices thus opened between the margins of the closure element 20 and the margins of the opening 18. The powder thus ejected deposits itself on the upper or outer side of the top-plate and its closure element so as to be accessible for use, and consequently may be taken up by means of a puff or other applicator and used as desired.

From the above description, it will be obvious that the present invention provides a

loose powder compartment structure for vanity boxes, which is of a very simple character, which comprises but few parts, and which is very easy of manipulation for the release of small quantities of powder and yet normally effective to retain the powder content against undesired escape.

The top plate 15 is easily removable from the shell or frame of the powder compartment, when it becomes necessary to replenish the latter. To render easy the removal of the top-plate 15, a notch 26 may be provided in its periphery for the insertion of any sharp pointed instrument to assist prying the same out of the shell or frame.

As many changes could be made in the above described constructions and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In a vanity box, a powder holding compartment, a top plate to normally close said compartment, said top plate having an opening in its body, a pivoted closure element at the underside of said top-plate to close its opening, and spring means fixed on said top-plate to engage the closure element so as to yieldably retain the same in closed position.

2. In a vanity box, means to define a loose powder compartment fixed within a section of said box, said means having an annular outwardly off-set seat portion around the mouth of said compartment, a top-plate frictionally engaged with said compartment defining means so as to be removable therefrom, said top-plate having an annular marginal bead receivable in said seat portion, said top-plate having an opening in its body, a pivoted closure element at the underside of said top-plate to close its opening, and spring means fixed on said top-plate to engage said closure element so as to yieldably retain the same in closed position.

3. In a vanity box, a frame fixed within a section of said box having an upstanding flange to define the sides of a loose powder compartment therein, a top-plate having a marginal flange to frictionally telescope into said first mentioned flange to removably retain said top-plate in assembled relation to said powder compartment, said top-plate having an opening in the body thereof, a pivoted closure element at the underside of said top-plate to close its opening, and a leaf spring member fixed to the underside of said top-plate to bear upwardly on the free end of said closure element to yieldably retain the same in closed position.

4. A top-plate for loose powder compartments of vanity boxes, said top-plate having

an opening in its body, a pivoted closure element at the under side of said top-plate to close its opening, and means cooperative with the free end portion of said closure element to yieldably retain the same in said closed position.

5. A top-plate for loose powder compartments of vanity boxes, said top-plate having an opening in its body, a pivoted closure element at the underside of said top-plate to close its opening, and a leaf spring member fixed to the underside of said top-plate to bear upwardly on the free end of said closure element to yieldably retain the same in closed position.

10 In testimony, that I claim the invention set forth above I have hereunto set my hand this 13th day of September, 1929.
